AUTOMATIC FREQUENCY CONTROL
SYSTEMCharles Travis, Philadelphia, Pa., assignor to
Radio Corporation of America, a corporation
of DelawareApplication May 3, 1935, Serial No. 19,563
Renewed April 16, 1937

15 Claims. (Cl. 250—20.36)

My present invention relates to frequency control systems, and more particularly to improvements in automatic frequency control networks.

There has been disclosed in my copending application Serial No. 4,793, filed February 4, 1935, patented August 25, 1942, as U. S. Patent No. 2,294,100, various circuits for automatically varying the tuning of a resonant circuit independently of the normal tuning device. In these previous systems the results sought to be accomplished have in general been attained. However, additional investigation and experimentation has resulted in the development of further improvements in automatic frequency control systems.

The automatic frequency control systems to be explained in detail in a later portion of this specification involve in general two distinct units. One of these units is a frequency discriminator, or frequency sensitive detector, that generates a bias varying with changes of the intermediate frequency signal carrier. The other unit is a control that is acted upon by the aforementioned bias, and whose function it is to vary the local oscillator frequency in a desired sense. The two units are so coordinated that if the intermediate frequency carrier tends to shift from its mid-band frequency value, the oscillator frequency changes sufficiently to restore proper alignment.

The automatic frequency control systems which comprise the subject matter of the present application are not only useful in facilitating the manual tuning operation of a superheterodyne receiver, but are also highly useful in maintaining the local oscillator frequency at a desired carrier setting for a long period of time, and throughout operation of the receiver during this period.

In addition to its aid and benefit in connection with the manual tuning of superheterodyne receivers, the presently disclosed frequency control systems can be used with benefit in connection with the automatic tuning of radio receivers of the superheterodyne type. In such instances the frequency control network functions as a vernier device to accurately tune the oscillator circuit after the automatic tuning mechanism has substantially adjusted the tuning device to its desired station position.

Accordingly, it may be stated that it is one of the primary objects of the present invention to provide improved automatic frequency control networks which are not only capable of usage in such a manner as to secure the aforementioned results, but are also constructed so as to function in a positive and reliable manner.

Another important object of the present invention is to provide automatic frequency control networks based on an operating principle which is substantially different from that utilized in connection with the circuits disclosed in my aforementioned patent. The present operation is based upon the fact that when the plate of the frequency control tube is coupled into the high potential side of the resonant circuit to be adjusted in tuning, and the grid of the control tube is excited by a voltage 90° out of phase with that appearing across the resonant circuit, then the plate current in the control tube is similarly out of phase with the resonant circuit voltage, and the control tube presents a reactive effect across the resonant circuit; the magnitude of this effective reactance varies according to the frequency control bias impressed upon the control grid of the control tube by the frequency discriminator network.

Another object of the present invention is to provide an automatic frequency control system for a superheterodyne receiver, the system comprising a frequency discriminator network functioning to provide a direct current bias which varies in magnitude with the shifting frequency of the intermediate frequency carrier; a reactance control tube being used in operative association with the local oscillator tank circuit in such a manner that the plate current of the control tube is out of phase with the tank circuit voltage whereby the control tube simulates a predetermined reactance across the tank circuit, the magnitude of the control reactance varying according to the discriminator bias which is impressed upon the control grid of the control tube.

Another object of the present invention may be said to reside in the provision of a tunable oscillation circuit which is capable of being automatically tuned to different frequencies in a predetermined frequency range, there being an automatic frequency control system operatively associated with the oscillation circuit in such a manner that the oscillation circuit is accurately and automatically tuned to resonance with a desired signal carrier when the tuning means of the oscillation circuit is adjusted to a predetermined frequency, there being provided additional means for rendering the frequency control operative as soon as the oscillation circuit has been tuned to approximate resonance with said predetermined frequency.

Still other objects of the invention are to improve generally the simplicity and efficiency of automatic frequency control systems for radio

receivers, and more especially to provide such systems in an economical and practical manner; the control systems of the present invention being particularly characterized by their reliability and accuracy in operation.

The novel features which I believe to be characteristic of my invention are set forth with particularity in the appended claims. The invention itself however, both as to its organization and method of operation, will best be understood by reference to the following description taken in connection with the drawings in which I have indicated diagrammatically several circuit organizations whereby my invention may be carried into effect.

In the drawings—

Fig. 1 diagrammatically shows a superheterodyne receiving system embodying one form of the present invention.

Fig. 2 shows a modification of the frequency control network in Fig. 1.

Fig. 3 shows a further modification of the frequency control network in Fig. 1.

Figs. 4, 5 and 6 show additional modifications of the frequency control network of Fig. 1.

Figs. 7 and 8 show two further modifications of the frequency control network.

Fig. 9 schematically illustrates the present invention applied to an automatic tuning device for a radio receiver.

Referring now to the accompanying drawings, wherein like reference characters in the different figures designate similar circuit elements, the receiving system shown in Fig. 1 is of the superheterodyne type, and is shown as embodying an automatic frequency control network whose general organization is similar to that disclosed, and claimed in my aforesaid patent.

The receiving system embodies generally a grounded antenna circuit A which feeds a radio frequency amplifier 1 having a tunable input which is resonated to the desired signal frequency. The output energy of the amplifier 1 is impressed upon the tunable input circuit 3 of a first detector tube 2, the latter being shown by way of illustration as of the 6A7 type. The plate circuit of the tube 2 includes a tuned circuit 4 which is resonated to the operating intermediate frequency of the system, and the latter may be chosen to have a value, for example of the order of 460 kilocycles (k. c.). The intermediate frequency energy produced in the circuit 4 may then be amplified in one or more stages of intermediate frequency amplification, and by way of example two such cascaded amplifier stages 5 and 6 are shown. The numeral 7 denotes the tuned input circuit of the amplifier 5, whereas the numeral 8 denotes the tuned output circuit of the amplifier.

The intermediate frequency amplifier 6 is provided with a tuned input circuit 9 and a tuned output circuit 10, it being pointed out that the circuits 4, 7, 8, 9 and 10, as well as the input circuit 11 to the second detector, are each resonated to the operating intermediate frequency of the system. The second detector or demodulator of the system may be of any well known type, and may follow the construction, for example, shown in my aforesaid patent. The local oscillator network comprises a tube 12 which is provided with a tunable oscillator tank circuit. The tank circuit includes the tuning condenser 13, and the series-arranged coil 14 and resistance R are connected in shunt with the condenser 13.

The high potential side of the tank circuit is connected to the control grid of tube 12 through a blocking condenser 15, the usual grid return resistor 16 being connected to ground from the grid side of condenser 15.

The cathode of oscillator tube 12 is grounded, and the plate thereof is regeneratively coupled to the tank circuit by means of a coil 14' which is magnetically coupled to coil 14. The positive potential required for the plate of oscillator tube 12 is fed to the plate through the feedback coil 14', and the low alternating potential side of the tank circuit is connected to a source of positive potential. This latter positive potential is provided for the plate of the frequency control tube to be described in further detail at a later point. The locally produced oscillations are impressed upon the grid 17, which is the nearest to the cathode of tube 2. The grid 17 is connected to the high alternating potential side of the oscillator tank circuit through a blocking condenser 18, the grid side of condenser 18 being connected to the cathode side of the grid bias network 20 by a resistor 19.

It will be observed that a dotted line denotes the mechanical uni-control device usually employed for operating the rotors of the variable tuning condensers of the signal and local oscillator circuits. It is to be clearly understood that the dotted line signifies the mechanical coupling between the rotors of condensers 13 and 3', and also with the rotors of the variable condenser usually employed in the input of amplifier 1. The frequency changing function in tube 2 is accomplished by means of electronic coupling, and this action is so well known to those skilled in the art at the present time that a mere reference thereto is believed sufficient.

The signal carrier amplitude at the demodulator input circuit 11 is maintained substantially constant over a wide range of carrier amplitude variation at the signal collector A by means of an automatic volume control arrangement, the latter being denoted as "AVC" in Fig. 1. The varying negative bias for securing the automatic amplification regulation is derived from the diode network operatively associated with the driver tube 21. The latter tube may be of the 78 or 6D6 type, and has its control grid coupled, for the impression thereon of intermediate frequency currents, to the high alternating potential side of the tuned output circuit 8 of amplifier 5. The signal path connected to the control grid of tube 21 includes a blocking condenser 22, the control grid being connected to ground through a grid return resistor 23.

The plate of tube 21 is connected to a source of positive potential through two paths; one of these paths includes the coil P₁, while the other path includes the coil P₂. Each of coils P₁ and P₂ is shunted by a condenser 24. The AVC diode network comprises the auxiliary anode 25 which is disposed adjacent a portion of the cathode of tube 21 outside the main electron stream to the plate of the tube. The grounded cathode lead of tube 21 includes the control grid bias network 26; the resistor 23 acting as a conducting path for the grid bias of the control grid of the driver tube. Intermediate frequency energy is impressed upon the diode anode 25 through the blocking condenser 27 which is connected between the plate of tube 21 and the diode anode 25. The diode anode 25 has connected in circuit therewith a load resistor 28, the latter developing a direct current voltage across it when the inter-

mediate frequency carrier amplitude attains a magnitude above a predetermined intensity level.

The anode side of resistor 28 is connected to the gain control electrodes of the controlled signal transmission tubes. In the present case the signal grids may act as the gain control electrodes, and the AFC lead is to be understood as being connected to the various grid circuits of the controlled transmission tubes. The AFC lead is connected to the anode side of resistor 28 through a resistor 29 which acts to suppress pulsating components of rectified intermediate frequency energy; the condenser 30 connected to ground cooperating with resistor 29 to provide the well known time constant network for the AFC arrangement.

Those skilled in the art will recognize that the system described to this point is in general of a well known type. Assuming that the signal range is in the present broadcast band and covers a range of frequencies from 550 to 1500 k. c., and the oscillator frequency is greater than the signal frequency, then the local oscillator frequency range will be from 1010 k. c. to 1960 k. c. if the operating intermediate frequency is to be 460 k. c. As the intermediate frequency carrier amplitude at circuit 8 increases the negative bias applied to the control grids of the regulated tubes by the AFC network increases thereby reducing the amplification of each tube, and in this way the signal amplitude at the demodulator input circuit 11 is maintained substantially uniform regardless of the signal amplitude variation at collector A.

The frequency discriminator network comprises the double diode tube 31, and the latter may be, by way of specific illustration of the 85 type with the triode section thereof unused. The anodes of tube 31, these anodes being designated by numerals 32 and 33, are connected to opposite sides of a resistor which develops the automatic frequency control (AFC) bias. This resistor has the cathode of tube 31 connected to the mid-point thereof, and therefore a single resistor may be employed or a pair of resistors of equal magnitude may be used instead. In any event the numeral 34 designates the resistor section between the cathode of tube 31 and the anode 32.

The resistor section 34' designates the load between the cathode of tube 31 and the diode anode 33. Each of the resistor sections 34 and 34' is shunted by a bypass condenser, and the anode side of resistor 34' is grounded. The secondary coil S_1 , which is magnetically coupled to primary P_1 , is connected between anode 32 and resistor section 34. The secondary coil S_2 is magnetically coupled to primary P_2 , and the secondary is connected between the anode 33 and the grounded side of resistor section 34'. A condenser 35 is connected in shunt with coil S_1 and tunes the latter to a frequency located on one side of the operating intermediate frequency value, whereas condenser 36 is in shunt with coil S_2 and tune the latter to a frequency located on the other side of the operating intermediate frequency.

The frequency control tube is shown by way of illustration as being of the pentode type, and its plate is connected by lead 37 to the high alternating potential side of the oscillator tank circuit. The cathode of control tube 38 is grounded through a grid bias network 39, and the control grid of tube 38 is connected to the anode side of resistor 34 through a path which includes the grid return resistor 40 and a lead 41. The lead 41 is designated by the letters "AFC" and is to be understood as denoting the automatic frequency control bias path. The lead 41 is adapted to be

connected to ground by a switch 42, and it will be understood that the automatic frequency control bias path for tube 38 is operative only when switch 42 is open. When the switch 42 is closed, then 5 the AFC path is short circuited to ground and is inoperative. The control grid of tube 38 is also connected to the upper end of resistor R in the tank circuit of the local oscillator through a blocking condenser 43, a bypass condenser 44 being connected between the low alternating potential side 10 of the tank circuit and ground.

In considering the operation of the AFC system of the receiver shown in Fig. 1 it is first pointed out that a high degree of selectivity in a superheterodyne receiver is of no great use unless it is possible to tune the receiver with a corresponding degree of accuracy, and thereafter to maintain this accuracy. As is well known, if the tuning of a superheterodyne receiver is inadequate the high selectivity may actually become a detriment. For example, in the all-wave or multiband receiver sets selectivity has been effectively increased 15 to 20 times over that usual for broadcast reception, merely because the received signal frequencies have been increased by that amount without changing the intermediate frequency band width, i. e., at 20 megacycles (mc.) the nominal 10 k. c. intermediate frequency band is only 0.05% of the base frequency. To meet 20 this increase in selectivity in present day receivers manual tuning means have been improved by the employment of more smoothly working speed reducing mechanical movements to operate the variable tuning condenser.

Nevertheless the maintenance of proper tuning after the station signal has once been correctly brought in, is a problem that requires a reliable and accurate solution. Local oscillator drift, if not corrected by more or less frequent manual 25 adjustment, is capable of mistuning the signal by many channels in the course of a few hours run. In the broadcast band conditions are quite as serious if quality of reproduction is a consideration. The average broadcast set user does not 30 tune the receiver well enough to obtain the best quality it is capable of giving; this is due not only to negligence, but to a great extent because of the lack of necessary skill, and in the latter case the mechanical design of the set is a contributing factor. These considerations show the 35 need for supplementing the accuracy of manual or automatic tuning by an automatic frequency control device.

It will therefore be seen that it is the essential 40 object of the frequency discriminator and frequency control tube to cooperate to adjust the oscillator frequency so as to make it appear as if the signal carrier frequency has been adjusted precisely to the center of its I. F. (intermediate frequency) band, and to anchor the receiver there in spite of small original maladjustments of tuning, or other causes, that subsequently arise from thermal changes and the like. It will now 45 be seen that the frequency discriminator network generates a bias, applied through lead 41, which varies with changes of the predetermined I. F. value; the control tube 38 has its gain varied by the AFC bias, and the control tube functions to 50 vary the local oscillator tank circuit in frequency. The discriminator and control units are so interrelated that if the I. F. carrier frequency tends to move away from the operating I. F. mid-band position, then the oscillator frequency changes sufficiently to restore the proper alignment. Such 55 units and their construction for performing these

functions are generally disclosed in my aforementioned patent.

The two similar I. F. transformers, between tube 21 and tube 31, have their primaries P₁ and P₂ connected in parallel in the plate circuit of the driver tube 21. This composite primary is tuned to the mid-band frequency of the I. F. band; in other words the composite primary is tuned to 460 k. c. The secondaries S₁ and S₂ are loosely coupled to their respective primaries and are tuned to different frequencies lying above and below the mid-band frequency by equal amounts. Thus, the secondary S₁ may be tuned to 462 k. c., and the secondary S₂ may be tuned to 458 k. c. The AVC diode is driven from the composite primary associated with the driver tube 21, and the diode load 28 not only functions as such, but also acts to damp the composite primary in order to aid in de-coupling the secondaries from each other and so causes them to act like isolated single tuned circuits.

The secondaries S₁ and S₂ are each connected into one of the plates of the double diode tube 31, and the cathode of this tube is "floating" for direct current voltage. One of the diodes returns to ground, and the AFC bias output is taken from the other diode return. The output of the discriminator is the algebraic difference between the rectified outputs of the two diodes. If the I. F. carrier frequency is off center frequency or the operating I. F. value towards the resonance of coil S₁, then the diode including anode 32 will produce the greater rectified voltage output of the two diodes, and the generated AFC bias will be negative with respect to ground. Conversely, if the I. F. carrier frequency is off in the other direction the reverse will be true. That is to say, the AFC bias will be positive in polarity. When the carrier frequency is exactly aligned the bias on the grid of tube 38 will equal the initial bias value thereof since the AFC bias will then be zero.

It will be noted that the AVC diode is driven from the driver tube which feeds the discriminator network. This mode of generating AFC bias is employed, in preference to deriving AFC input energy from the circuit 11, because there is thus obtained a higher carrier input into the AFC rectifier. A considerable voltage delay may be used on the AVC diode. Another advantage of taking off the AFC bias in this manner is that the signal modulation at the second detector is not distorted by the demodulation produced by the AVC diode.

If the AFC driver tube also drives the AVC rectifier its output is automatically held nearly constant no matter where it is connected. Therefore, the grid of the driver tube may be connected at the primary or secondary of the transformer preceding the last I. F. amplifier tube. This has the merit of giving a broader channel for the AFC and the AVC than for the audio detector. The gain of the last I. F. stage should be considerably decreased to avoid second detector overload.

As clearly explained in my aforementioned patent maximum AFC sensitivity is obtained when the discriminator characteristic has the greatest slope. This occurs when the two secondaries S₁ and S₂ are so tuned that points of maximum slope on their individual resonance curves are made to coincide. The control circuit acts to vary the oscillator frequency and this variation may be thought of as if due to a variation in capacity, or of an inductance. The total tank circuit reactance may be considered to consist of two parts,

viz., that part physically present as in the variable tuning condenser, or the tuning coil, and that part reflected by the control tube circuit. The latter is a function of the I. F. carrier frequency, and its magnitude varies with the carrier frequency shift from I. F. mid-band frequency.

In my aforementioned patent the control tube has been shown as reflecting capacity into the tank circuit, or the plate resistance of the control tube has been connected in series with a reactive element in the tank circuit. Additional investigation and experimentation have revealed frequency control circuits which make use of a different principle. It will be noted that the plate 10 of control tube 38 is coupled into the high potential side of the tank circuit, and that the grid of the control tube is excited by an alternating voltage which is 90° out of phase with that appearing 15 across the tank circuit. The plate circuit in the control tube is then likewise out of phase with the tank voltage, and accordingly the plate to cathode impedance of control tube 38 looks like a reactance to the tank circuit.

The sign of the reactance presented to the tank 20 circuit by the control tube depends upon the nature of the impedance across which is developed the alternating voltage to be fed to the input electrodes of the control tube. The magnitude of the reflected reactance depends upon the 25 value of the AFC bias impressed upon the control grid of control tube 38, as this varies the mutual conductance, and proportionately the magnitude of the plate current, of the control tube. In Fig. 1 there is shown one method of obtaining the 30 out-of-phase excitation for the grid of the control tube, and it will be noted that this is accomplished by taking the alternating voltage across resistance R. The effect of this arrangement is to produce an inductive effect across the tank coil 14. 35 In other words, the plate to cathode impedance of tube 38 simulates an inductive reactance across coil 14. As the plate current of tube 38 is decreased the shunting effect of the reflected or simulated inductance is decreased, and the effective inductance of the tank circuit will therefore 40 increase. This results in a decrease of oscillator frequency.

A specific example will be given to illustrate the 45 operation of the control tube 38. Assume that the set is to be tuned to a signal of 600 k. c.; the local oscillator frequency if higher will have to be 1060 k. c. to produce an I. F. of 460 k. c. As the tuner device is adjusted from 500 to 600 k. c., the 50 oscillator condenser 13 tunes the tank circuit from 960 to 1060 k. c. When the tank circuit is within 2 k. c., for example, of 1060 k. c. (1058 k. c.), the I. F. value is 458 k. c. Since this is the 55 frequency of the circuit S₂, rectified voltage will be developed across resistor 34'. The control 60 grid of tube 38 will, therefore, become less negative than its initial negative bias value with respect to ground due to its connection through lead 41 and resistor 34 to the cathode side of resistor 34'. The plate current flow of tube 38 increases; 65 this will result in an increase in the inductive reactance reflected across coil 14. Thus, the effective inductance in the tank circuit decreases; the oscillator frequency, therefore, increases.

The increase in frequency of the tank circuit 70 will be such as to bring the local oscillation frequency to 1060 k. c. Then the proper I. F. value of 460 k. c. is secured, and the set sounds "tuned-in" to the listener. The reverse action takes place, of course, when the set is tuned away from the desired setting of 600 k. c. Within 2 k. c. on

either side of 600 k. c. the AFC system will act to "anchor" the tuning of the receiver. When the receiver is tuned beyond the permissible limits of a carrier setting, the AFC action is suspended until the limit of the adjacent channel is reached. In this way the normally highly selective super-heterodyne receiver is rendered easily tunable; a range of some 4 k. c., for example, is provided within which the set may be turned and yet distortionless reproduction be secured. The same operation is secured when the local oscillator circuit constants vary due to thermal, or other, effects. The AFC acts to bring the oscillator frequency back to the desired operating value so as to produce the operating I. F.

There are numerous methods of obtaining the out-of-phase grid voltage for the control tube 38. In order to make it clear to those skilled in the art how such different modes of procedure may be achieved, the following analysis of the operation of tube 38 and its circuits is furnished. It is to be clearly understood, however, that the analysis is theoretical in nature, and in no way affects the demonstrated operation of the reactance control network.

It can be shown, in general, for an oscillator network of the type illustrated in Fig. 1 (that is, the tank circuit and the tube 38 with its circuits) that the combination of the control tube 38 and the oscillator presents to the tank circuit an effective impedance which is the negative reciprocal of the control tube impedance with respect to the resistance product of both oscillator and control tubes. For example, a capacity is the reciprocal of an inductance with respect to a resistance product; the reciprocal of a shunt combination is a series combination.

A practical resistance value for resistor R in Fig. 1, for a broadcast local oscillator, is about 100 ohms. With the G_m (mutual conductance) of tube 38 equal to 1000 micromhos, the frequency change is about 5 percent. This permits a variation of plus or minus 25 k. c. at 1 mc., which seems ample for the purpose. The tuned impedance of the tank circuit is unaffected by the control action. Constant oscillator amplitude with frequency change is one of the advantages of the present arrangement.

The series resistor R is not confined to the inductive leg of the tank circuit. For example, and as shown in Fig. 2, the resistor R₁ is placed in the capacitive leg of circuit 13-14. In this case the control tube cathode to plate impedance will appear as a resistance-capacity arm across the tank circuit; increase in the G_m of the control tube will now lower the oscillator frequency. It is necessary, in this case, to reverse the AFC connection to the discriminator network. Lead 61 is, therefore, connected to the anode side of resistor 34' and the anode side of resistor 34 is grounded.

Another method of securing the out-of-phase grid voltage for tube 38 is shown in Fig. 3. Here the reactive element is condenser C which is in series with the oscillator tickler coil 14'. Condenser C is grounded, and choke 50 is used to feed the direct current voltage to the plate of oscillator tube 12. The current flowing in the external plate circuit of tube 12 is in phase with the tank circuit voltage. A reactive element in the plate circuit will, therefore, develop an out-of-phase voltage which is impressed upon the control grid of tube 38. The cathode to plate impedance of tube 38 presents a negative inductance across the tank circuit; the net result is an in-

crease in effective inductance in the oscillator tank circuit. The AFC connection must, then, be reversed in polarity with respect to that shown in Fig. 1.

5 If the capacitive reactance C is replaced by an inductance coil then a negative capacity will be reflected across the tank circuit. If a negative inductance, say the mutual of a transformer, were used in place of C, it would be reflected as a positive capacity. Any resistive element reflects as a negative resistance, or conductance, and tends to aid the feedback of the oscillator.

In Fig. 4 is shown a modification of the method of securing out-of-phase voltage; it differs from 15 that of Fig. 3 in that the out-of-phase voltage is taken from across the tickler coil 14'. The plate to cathode impedance of the control tube, in this case, presents a negative capacity across the tank circuit. It is not necessary to change the 20 AFC connection to the discriminator network from that shown in Fig. 1.

It may be that the reflected reactance from the tank circuit will give rise to an in-phase component across coil 14'. This may be eliminated

25 by using the arrangement shown in Figs. 5 and 6. In Fig. 5 the coil L₁ is coupled to tickler 14', it is not coupled to tank coil 14. The out-of-phase voltage across coil L₁ is impressed upon the control grid of tube 38 through coil L₂; the latter 30 coil is coupled to coil L₁. The plate to cathode impedance of control tube 38 presents a negative capacity across the tank circuit; the AFC connection is the same as that in Fig. 4. In Fig. 6 is shown the effect of reversing the end 35 connections of coil L₂. The plate to cathode impedance of tube 38 now presents a positive capacity across the tank circuit. The AFC connection must be reversed in polarity as shown. It is, further, pointed out that the circuit of Fig. 3, wherein the out-of-phase voltage is derived across C, can be used to avoid the in-phase component of 40 Fig. 4.

Actual experience with automatic frequency control circuits of the type referred to herein 45 has shown that the out-of-phase voltage for the control tube 38 is best secured from across a condenser. This causes the plate to cathode impedance of the control tube to produce an inductance variation, and realizes a range and 50 sensitivity of control which are proportional to frequency over each particular tuning band. Equal bias change on the control tube will produce equal change in the tank circuit inductance; with capacity as the tuning element this will give 55 equal percent frequency change. Under certain conditions of use the control tube may be affected by the oscillator; a certain degree of self-maintained frequency modulation may occur.

This is effectively prevented by using the 60 arrangement shown in Fig. 7. In this case the condenser C₁, which supplies the out-of-phase voltage to control tube 38, is in the plate circuit of the electron coupled oscillator tube 12'. The oscillator tube 12' is shown of the 6A7 type 65 by way of specific illustration, and uses the normal electrode voltages shown. The fourth grid of the oscillator is not used, but is bypassed to the cathode by a condenser and given a fixed bias of -3 volts. The condenser C₁ coupling 70 to the control grid of tube 38 is placed in the plate circuit of the 6A7 tube with parallel plate voltage feed around it through a radio frequency choke coil 60. A resistor 61 in series with tickler coil 14' in the plate voltage line to the oscillator tube serves to reduce the voltage to the 75

proper value for the oscillator anode grid 18'.

It will be noted that the first grid functions as the oscillator grid, and is coupled to tank circuit 13-14 through the condenser 62. The tickler coil 14' regeneratively couples the second or anode grid to the tank circuit. Local oscillations for the grid 17 of the mixer tube 2 (Fig. 1) are tapped off from any desired point on coil 14. Similarly the plate of control tube 38 may be adjustably connected to any desired point on coil 14. These adjustable connections to coil 14 may be used in connection with any of the other arrangements if desired. The alternating current component of the plate current of the tube flows through condenser C1 and gives the necessary out-of-phase alternating voltage for the control grid of tube 38. Since the alternating current component of plate current flows out of a high plate resistance, and condenser C1 is connected right across the plate, the circuit is not complicated.

The condenser C1 and choke 60 may be replaced by the primary winding of an I. F. transformer. In the broadcast band this combination of condenser and choke may resonate just under the lowest frequency of the band so that the effective value of C1 for oscillator frequency is less at the low end of the band resulting in more uniform AFC sensitivity.

In Fig. 8 there is shown a variation of the arrangement of Fig. 7; in this case the oscillator is shown as including a pentode tube of the same type as tube 38. The oscillator tube 11 has its cathode magnetically coupled, as at M1, to the tunable tank circuit 12. The plate of tube 38 is connected by lead 13 to the grid side of tank circuit 12. The plate of oscillator 11 is fed with positive voltage through coil 10; the condenser C2 feeds the out-of-phase alternating voltage to the input grid of tube 38 through blocking condenser 43.

In Fig. 9 there is shown, in schematic manner, the application of the invention to an automatic tuner device. The automatic tuner mechanism is that shown in U. S. patent to C. R. Garrett No. 1,956,419, granted April 24, 1934. The tuning condensers are automatically varied by the tuning motor to a desired position when a station control switch is depressed. The condenser 13 is that in the oscillator tank circuit. The AFC system is to be understood as being that of Fig. 1. In fact, the entire system may be that of Fig. 1, or any of the AFC networks of the other figures. The switch 42 is the switch of Fig. 1 which is capable of short-circuiting the AFC line when closed. The movable element 42' of switch 42 is coupled to the armature 90 of a solenoid; an insulation spacer 91 is provided between 42' and 90.

The armature 90 carries a winding 92 which is connected to the tuning motor armature current supply. A fixed field current winding 93 causes the element 42' to contact the other element of switch 42 whenever the tuning motor is operating and varying the condensers. When the tuning motor ceases to run, the armature 90 is pulled back by spring 94; this opens switch 42 and the AFC is operative.

Thus, in Fig. 9 there is shown a system capable of vernier tuning after rough tuning by an automatic tuner. The AFC here operates to bring the tank circuit into exact tune after the tuning motor has stopped running. As long as the motor is turning the condenser rotors, the switch 42 is closed. This renders the AFC inoperative be-

cause the switch 42 short circuits the AFC system. The flexibility of the present invention in so far as variety of uses is concerned will now be seen.

5 In any of the systems shown in Figs. 1 to 8 inclusive, the control tube 38 can be a sharp cut-off R. F. (radio frequency) pentode such as the 6C6 type tube. The coupling to the mixer tube from the local oscillator is not limited to that shown in Fig. 1. In the arrangement of Fig. 7, for example, the grid fourth from the cathode may have signals impressed thereon. This would permit the 6A7 tube shown there to act as a combined oscillator-first detector.

10 15 The control tube 38 should be operated at conservative voltages so that its life will exceed that of the other tubes. Further, a push-pull variant of the single side circuit may be used to prolong the life of the control tube. The AFC action should be slower than the AVC. This is to prevent a signal from being brought into the center of the band, where gain is high, more rapidly than the gain can be reduced by AVC action; otherwise momentary blasting will result. However, the 20 25 AFC network should have a smaller time constant than the power supply unit in order that it may follow and prevent changes in oscillator frequency due to changes in line voltage.

While I have indicated and described several 30 systems for carrying my invention into effect, it will be apparent to one skilled in the art that my invention is by no means limited to the particular organizations shown and described, but that many modifications may be made without departing 35 from the scope of my invention, as set forth in the appended claims.

What I claim is:

1. A superheterodyne receiver comprising a frequency changer network including a tunable 40 local oscillator circuit, an intermediate frequency network, means for demodulating the intermediate frequency energy, a discriminator network, connected to the intermediate network, to have intermediate frequency energy impressed thereon, constructed and arranged to produce a direct current voltage whose magnitude is solely dependent upon the frequency of said impressed energy, an electron discharge tube including at least an output electrode and a pair of input 45 electrodes and having its output electrode connected to the oscillator circuit, a phase shifter in the oscillator circuit, said phase shifter including a resistor element across which is developed an alternating voltage substantially in quadrature with the output electrode alternating potential of said electron discharge tube, said resistor element cooperating with one of the reactive tuning elements of said tunable oscillator circuit to provide said phase shifter, means for impressing 50 said quadrature voltage upon the input electrodes of said tube, and means for impressing the direct current voltage produced by said discriminator upon an input electrode of said tube whereby the 55 frequency of said local oscillator circuit may be adjusted in a predetermined direction.

2. A superheterodyne receiver comprising a frequency changer network including a tunable local oscillator circuit, an intermediate frequency network, means for demodulating the intermediate frequency energy, a discriminator network, connected to the intermediate network, to have intermediate frequency energy impressed thereon, constructed and arranged to produce a direct current voltage whose magnitude is solely dependent upon the frequency of said impressed 70 75

energy, an electron discharge tube including at least an output electrode and a pair of input electrodes and having its output electrode connected to the oscillator circuit, a phase shifter in the oscillator circuit, said phase shifter consisting of a reactive component of the tunable circuit and a resistor element, said resistor element being chosen to develop thereacross an alternating voltage substantially in quadrature with the output electrode alternating potential of said electron discharge tube, means for impressing said quadrature voltage upon the input electrodes of said tube, and means for impressing the direct current voltage produced by said discriminator upon an input electrode of said tube whereby the frequency of said local oscillator circuit may be adjusted in a predetermined direction.

3. In combination with a resonant circuit including a condenser and coil, an electron discharge tube provided with at least an anode and a pair of input electrodes and having its anode connected to a point of relatively high alternating potential on said resonant circuit, a phase shifter in said resonant circuit, said phase shifter consisting of a resistor element in series with said resonant circuit condenser, connections from the input electrodes of said tube to said resistor for impressing the alternating voltage developed across said resistor upon the input electrodes of said tube, said voltage being substantially in quadrature with the alternating potential at the anode of said tube, and means for varying the space current flow of said tube.

4. In combination with a resonant circuit including a condenser and coil, and said condenser being variable to tune the circuit over a wide range of frequencies, an electron discharge tube provided with at least an anode and a pair of input electrodes and having its anode connected to a point of relatively high alternating potential on said resonant circuit, an impedance connected in said resonant circuit, connections from the input electrodes of said tube to said impedance for impressing the alternating voltage developed across said impedance upon the input electrodes of said tube, said voltage being substantially in quadrature with the alternating potential at the anode of said tube, means for varying the space current flow of said tube in response to variations in frequency of said resonant circuit within predetermined limits of adjustment settings of said resonant circuit variable condenser, and said impedance being a resistance in series with the coil of said resonant circuit.

5. In combination with a resonant circuit including a condenser and coil, and said condenser being variable to tune the circuit over a wide range of frequencies, an electron discharge tube provided with at least an anode and a pair of input electrodes and having its anode connected to a point of relatively high alternating potential on said resonant circuit, an impedance connected in said resonant circuit, connections from the input electrodes of said tube to said impedance for impressing the alternating voltage developed across said impedance upon the input electrodes of said tube, said voltage being substantially in quadrature with the alternating potential at the anode of said tube, means for varying the space current flow of said tube in response to variations in frequency of said resonant circuit within predetermined limits of adjustment settings of said resonant circuit variable condenser, and said impedance being a resistance in series with the condenser of said resonant circuit.

6. In combination with a local oscillator network of a superheterodyne receiver, said oscillator network including an electron discharge tube having a cathode, a plate and at least two auxiliary electrodes, a tunable tank circuit connected to one of the auxiliary electrodes, and means for regeneratively coupling the other auxiliary electrode to said tank circuit, a frequency control tube provided with at least a plate and a pair of input electrodes, the control tube having its plate connected to a point of relatively high radio frequency potential on said tank circuit, a condenser in the plate circuit of said oscillator tube across which is developed an alternating voltage substantially 90° out of phase with the alternating potential at the plate of said control tube, connections for impressing said out of phase voltage upon the input electrodes of said control tube, and means for varying the plate current flow of said control tube.

7. In combination with an electron discharge tube having input and output circuits reactively coupled to produce oscillations, at least one of the coupled circuits being resonant to a desired oscillation frequency, means for varying the frequency of the resonant circuit comprising a tube having at least an input electrode and an output electrode, means feeding alternating current from the second tube output electrode to a point of relatively high potential of said resonant circuit, means including a condenser electron coupled to said resonant circuit, for impressing upon said input electrode alternating voltage derived from the oscillation tube which is in phase quadrature with the alternating potential at the output electrode of the second tube, and means for controlling the gain of said second tube.

8. In combination with an electron discharge tube having input and output circuits reactively coupled to produce oscillations, at least one of the coupled circuits being resonant to a desired oscillation frequency, means for controlling the frequency of the resonant circuit comprising a tube having at least an input electrode and an output electrode, means feeding alternating current from the second tube output electrode to a point of relatively high potential of said resonant circuit, means, including a reactance electronically coupled with said resonant circuit, for impressing upon said input electrode alternating voltage derived from the oscillation tube which is in phase quadrature with the alternating potential at the output electrode of the second tube, and means for controlling the gain of said second tube.

9. In combination with an electron discharge tube having input and output circuits reactively coupled to produce oscillations, at least one of the coupled circuits being resonant to a desired oscillation frequency, means for adjusting the frequency of the resonant circuit comprising a tube having at least an input electrode and an output electrode, means connecting the second tube output electrode to a point of relatively high potential of said resonant circuit, means for impressing upon said input electrode alternating voltage derived from the oscillation tube which is in phase quadrature with the alternating potential at the output electrode of the second tube, and means for controlling the gain of said second tube, said impressing means including a reactance in the space current path of the oscillation tube and electron coupled to said resonant circuit.

10. In combination with an oscillatory system

provided with an oscillator tube and a resonant tank circuit provided with a tuning reactance, an electron discharge device provided with a cathode and at least a positive output electrode and an input electrode, means connecting the cathode to output electrode impedance of said electron device across said tank circuit, a phase shifter for said tank circuit comprising said tuning reactance and a resistance in series, said resistance being located between the input electrode and cathode of said electron device, said resistance providing thereacross an alternating voltage substantially phase-shifted relative to the tank circuit voltage, means applying said phase-shifted voltage to said input electrode thereby to cause said impedance to exercise an essentially reactive effect on said tank circuit, and means for varying the electron flow to said output electrode in response to a variable voltage thereby to vary said reactive effect.

11. In combination with an oscillatory system provided with an oscillator tube and a resonant tank circuit, means for varying the frequency of the oscillations produced by said system, said means comprising an electron discharge device provided with a cathode and at least a positive output electrode and an input electrode, means connecting the cathode to output electrode path of said electron device across said tank circuit, a phase shifter element, means in said oscillator tube electronically coupling said element to said tank circuit, said element providing thereacross an alternating voltage phase-shifted substantially 90 degrees relative to the tank circuit voltage, means applying said phase-shifted voltage to said input electrode thereby to cause said impedance to exercise an essentially reactive effect on said tank circuit, and means for varying the electron flow to said output electrode in response to a variable voltage thereby to vary said reactive effect.

12. In combination with an oscillatory system provided with an oscillator tube and a resonant tank circuit, said tank circuit comprising at least two reactive elements of opposite sign co-operating to tune the system to a desired frequency, means for varying the frequency of the oscillations produced by said system, said means comprising an electron discharge device provided with a cathode and at least a positive output electrode and an input electrode, means connecting the cathode to output electrode impedance of said electron device across said tank circuit, a resistor electrically associated with one of said two reactive elements to provide a phase shifter, said resistor being chosen to provide an alternating voltage phase-shifted substantially 90 degrees relative to the tank circuit voltage, means applying said phase-shifted voltage to said input electrode thereby to cause said impedance to simulate a reactance in said tank circuit, and means for varying the electron flow to said output electrode in response to a variable voltage thereby to vary said simulated reactance.

13. In combination with an oscillatory system provided with an oscillator tube and a resonant tank circuit, said oscillator tube having a cathode and at least two cold electrodes forming an oscillator section, said tube including an additional output electrode electron coupled to said oscillator section, an electron discharge device provided with a cathode and at least a positive

anode and an input grid means connecting the cathode to anode impedance of said electron device across said tank circuit, a phase shifter comprising a capacitance, said capacitance being located between the input grid and cathode of said electron device, said capacitance providing thereacross an alternating voltage phase-shifted relative to the tank circuit voltage, means applying said phase-shifted voltage to said input grid thereby to cause said impedance to exercise an essentially reactive effect on said tank circuit, and means for varying the electron flow to said anode in response to a variable voltage thereby to vary said reactive effect.

14. In combination with an oscillatory system provided with an oscillator tube and a resonant tank circuit, said tank circuit comprising at least two parallel-connected reactive elements of opposite sign co-operating to tune the system to a desired frequency, means for varying the frequency of the oscillations produced by said system, said means comprising an electron discharge tube provided with a cathode and at least a positive output electrode and an input electrode, means connecting the cathode to output electrode impedance of said electron device across said tank circuit, said last means including a direct current connection from said output electrode to the high alternating potential side of said tank circuit, a resistor electrically connected in series with one of said two reactive elements to provide a phase shifter, said resistor being chosen to provide an alternating voltage phase-shifted substantially 90 degrees relative to the tank circuit voltage, means applying said phase-shifted voltage to said input electrode thereby to cause said impedance to simulate a reactance in said tank circuit, said applying means comprising a direct current blocking condenser connected from the junction of said resistor and one reactive element to said input electrode and means for varying the electron flow to said output electrode in response to a variable voltage thereby to vary said simulated reactance.

15. In combination with an oscillatory system provided with an oscillator tube and a resonant tank circuit, means for varying the frequency of the oscillations produced by said system, said means comprising an electron discharge tube provided with a cathode and at least a positive output electrode and an input electrode, means connecting the cathode to output electrode path of said electron discharge tube across said tank circuit, a phase shifter element, said oscillator tube comprising a cathode, control grid, positive screen grid and positive plate, said cathode, control grid and screen grid being coupled to the tank circuit to provide said oscillations, means connecting said phase shifter element in circuit with said plate for electronically coupling said element to said tank circuit, said element providing thereacross an alternating voltage phase-shifted substantially 90 degrees relative to the tank circuit voltage, a condenser applying said phase-shifted voltage to said input electrode thereby to cause said impedance to exercise an essentially reactive effect on said tank circuit, and means for varying the electron flow to said output electrode in response to a variable voltage thereby to vary said reactive effect.

CHARLES TRAVIS.
